(57) **CLAIM**

The ornamental design for a boat chair, as shown and described.

DESCRIPTION

FIG. 1 is a front, right, top perspective view of a boat chair, showing my new design;

FIG. 2 is a rear, left, bottom perspective view thereof;

FIG. 3 is a front elevational view of the enlarged scale thereof;

FIG. 4 is a rear elevational view of the enlarged scale thereof;

FIG. 5 is a left side view thereof;

FIG. 6 is a right side view thereof;

FIG. 7 is a top plan view of the enlarged scale thereof;

FIG. 8 is a bottom plan view of the enlarged scale thereof; and,

FIG. 9 is a front, right, top perspective view of the boat chair in an alternate configuration.

The dashed broken lines in the figures are for the purposes of illustrating portions of the boat chair and form no part of the claimed design.

The short-short-long dashed broken lines immediately adjacent to the claimed areas in the views represent the boundaries of the design and form no part of the claimed design.
